A. P. DARLEY

ATTACHMENT FOR STOVEPIPES

Filed Oct. 13, 1923

Alfred P. Darley
INVENTOR

BY Victor J. Evans

ATTORNEY

UNITED STATES PATENT OFFICE.

ALFRED P. DARLEY, OF CEDAREDGE, COLORADO.

ATTACHMENT FOR STOVEPIPES.

Application filed October 13, 1923. Serial No. 668,432.

To all whom it may concern:

Be it known that I, ALFRED P. DARLEY, a citizen of the United States, residing at Cedaredge, in the county of Delta and State 5 of Colorado, have invented new and useful Improvements in Attachments for Stove-pipes, of which the following is a specification.

This invention relates to an attachment 10 for stove pipes and more particularly to a new construction of stove pipe elbow whereby stove pipes will be more efficiently cleaned.

An object of the invention is the construction 15 of a simple device that may be removed to allow the insertion of an instrument into the pipe for cleaning purposes.

A feature of my invention is the novel 20 manner of constructing a plate and associating same with clips so that the plate will be effectively held against accidental displacement.

With these and other objects in view the 25 invention will be better understood from the following detailed description taken in connection with the accompanying drawing wherein:

Fig. 1 is a side elevation of the invention.

Fig. 2 is a top plan view.

30 Fig. 3 is a sectional view on the line 3—3 of Fig. 2.

Fig. 4 is a detail enlarged view of the cover.

Again referring to the drawing illustrating 35 one of the many constructions of my invention the numeral 1 designates a stove pipe shown in this particular instance as a stove pipe elbow. This pipe is formed with an elongated opening 2 so that a brush or other instrument may be readily inserted 40 therethrough and operated to clean the inside of the stove pipe. An arcuate shaped plate 3 is adapted to cover the opening and

is of a size to overlap the edge of the opening as indicated at 4. Clips 5 are provided 45 having ends 6 upturned so that the clips may be frictionally and yieldably forced over the plate for holding the same in place. A rivet 7 secures each clip to the pipe for 50 arcuate swinging movement. Also mounted 50 on this rivet is a washer 8 that engages in an arcuate depression 9 in the plate and thus the plate is held against accidental displacement but may be readily removed when 55 necessary.

From the foregoing description taken in connection with the accompanying drawing it will be apparent that I provide an attachment that may be readily manipulated for 60 allowing quick access to the interior of the pipe in a manner that same may be thoroughly cleaned.

It will also be noted that the device is of simple construction and may be manufactured at a relatively low cost and I wish it 65 to be understood that the plate may be given various other shapes and a different construction of clips may be used without departing from the spirit of this invention, and, therefore, I do not desire to be limited 70 in any manner except as set forth in the claim hereunto appended.

Having thus described my invention what I claim is:

A stove pipe elbow having an opening 75 therein, a plate for closing the opening and overlapping the edge of the opening, said plate having an arcuate depression in each end, a pin carried by the elbow adjacent each end of the opening, a washer on each 80 pin fitting into the depression of the plate and yieldable clips carried by the pins for engagement with the outer face of the plate to retain the same against displacement.

In testimony whereof I affix my signature.

ALFRED P. DARLEY.
